UNITED STATES PATENT OFFICE.

ABRAHAM SLOTOROFF, OF BROOKLYN, NEW YORK, ASSIGNOR, BY DIRECT AND MESNE ASSIGNMENTS, TO SASCO KNITTED HAT COMPANY, OF NEW YORK, N. Y., A CORPORATION OF NEW YORK.

DESIGN FOR A CAP.

60,272.

Specification for Design.

Patented Jan. 17, 1922.

Application filed June 7, 1921. Serial No. 475,724. Term of patent 7 years.

To all whom it may concern:

Be it known that I, ABRAHAM SLOTOROFF, a citizen of the United States, and resident of the borough of Brooklyn, in the county of Kings, city and State of New York, have invented a new, original, and ornamental Design for a Cap, of which the following is a specification, reference being had to the accompanying drawing, forming a part hereof.

In the drawing, Fig. 1 is a side view;

Fig. 2 a rear view;
Fig. 3 a front view; and
Fig. 4 a top plan view, of a cap, showing my new design.

I claim:

The ornamental design for a cap, as shown.

ABRAHAM SLOTOROFF.
